A. Milton Parker

UNITED STATES PATENT OFFICE.

ARTHUR MERTON PARKER, OF LOS ANGELES, CALIFORNIA.

SEWING-AWL.

SPECIFICATION forming part of Letters Patent No. 778,066, dated December 20, 1904.

Application filed December 9, 1903. Serial No. 184,503.

To all whom it may concern:

Be it known that I, ARTHUR MERTON PARKER, a citizen of the United States, residing at Los Angeles, in the county of Los Angeles and State 5 of California, have invented a new and Improved Sewing-Awl, of which the following is a full description.

My invention is an improvement in the class of sewing-awls whose handles are provided 10 with a recess or chamber to receive a thread-wound spool from which the thread passes to the eye of the awl-point and is drawn off as required.

The invention consists of novel features and 15 parts and combination of same, as will be fully described hereinafter and then pointed out in the claims.

A practical embodiment of the invention is represented in the accompanying drawings, 20 forming a part of this specification, in which similar characters of reference indicate corresponding parts in all the views.

Figure 1 is a perspective view of the improvement. Fig. 2 is a sectional plan view 25 of the same on the line 2 2 in Fig. 3. Fig. 3 is a transverse section of same on the line 3 3 in Fig. 2; and Fig. 4, a view of the spring-lock *f* with end of spool-holder *e* locked in hole *j* by spring-snap *k*, which engages with 30 the groove *l*. The dotted lines show the lock *f* open.

The improved sewing-awl is provided with a suitable handle *A*, carrying at its front end 35 a chuck *B* for receiving and holding a needle *C* of any approved construction. Extending diagonally from the front end of the handle is arranged a chamber *D*, through which extends a spool-holder *E* in the form of a shaft secured to handle *A* in the rear of the chamber *D*, as is plainly indicated in Fig. 2. The front end of the spool-holder *E* is secured by 40 a spring-lock *F*, adapted to be opened, as indicated by the dotted lines, and allowing the removal of an empty spool *G* from the spool-holder or placing a filled spool on said holder 45

within the chamber *D*. The spool *G* carries the usual thread *H*, which unwinds from the spool and extends first transversely through the diagonal slot *I*, extending from the chamber *D* through the handle *A*, the thread *H* 50 leading from the outer side of the slot *I* to the eye of the needle *C*, as is indicated in the drawings.

In using the device the operator takes hold of the handle *A* in such a manner that the fingers extend across the slot *I*, thereby governing the unwinding and tension of the thread 55 in the operation of sewing.

By the arrangement described a nearly closed handle is provided, with no loose parts 60 to fall out or be mislaid. By having the chamber *d* extending diagonally from the front of the handle no plugs or lids are required for a bearing for the hand, and the spool can be secured or withdrawn for refilling by closing or opening the spring-lock, as indicated in the drawings. By having the slot *i* diagonal through the handle it places it parallel with the diagonal chamber, which allows the easy passage of the thread from the spool 70 to the needle. The needle *C* is provided with the usual eye for the passage of the thread, and the said needle is also preferably provided with the usual longitudinally-extending recesses in the rear of each side of the eye for the easier 75 passage of the needle with the thread through the material to be sewed.

Having thus described my invention, what I claim, and desire to secure by Letters Patent, is—

1. An awl, comprising a handle having a chamber extending diagonally with respect to the longitudinal axis of the handle, from the forward end to nearly the rear of the handle, a shaft or spool-holder in the chamber adapted to hold the spool with the thread thereon, one end of the shaft or spool-holder extending through and fastened in the rear of the chamber and a spring-lock in the forward end of the chamber adapted to secure the forward end 85 90

of the spool-holder and retain the spool within the chamber.

2. A sewing-awl comprising a handle provided with a diagonally-arranged chamber, 5 with respect to the longitudinal axis of the handle, a spool with the thread thereon in the said chamber, and a spring-lock adapted to retain the spool within the chamber.

In testimony whereof I have signed my name to this specification in the presence of two sub- 10 scribing witnesses.

ARTHUR MERTON PARKER.
